ELECTRIC FIXTURE

Arthur A. Johnson, New Bedford, Mass., assignor
to John I. Paulding, Inc., New Bedford, Mass.,
a corporation of Massachusetts

Application November 6, 1935, Serial No. 48,509

9 Claims. (Cl. 240—73)

This invention relates to electric light fixtures and is exemplified in a wall bracket for electric lamps.

The main object of the invention is the provision of an electric light fixture of simple and light construction which may be easily and rapidly assembled.

A further object of the invention is the provision of an insulating body of such form that a lamp socket may be mounted therein by insertion from the back of the insulating body.

An additional object is to provide simple means for locking the lamp socket within the insulating body to hold it fixed against movement in any direction.

Another object is the provision of a fixture having a convenience outlet for receiving a plug for operating from said fixture auxiliary electric devices such as vacuum cleaners, toasters and similar articles.

Yet another object of the invention is the provision of a fixture having a one-piece insulating body of such form that it may be molded from suitable material in one operation by the use of suitable dies.

Various objects of the invention will be described hereinafter.

My invention contemplates the provision of a fixture comprising a hollow shell of light construction, molded in one piece from porcelain or other suitable insulating material and preferably having a base portion of any suitable form for engaging a wall or other supporting surface with a projecting portion for holding a lamp socket, the projecting portion having an opening through which an electric lamp may be threaded into the lamp receiving screw shell of the socket in register with said opening. The shell is so formed that a lamp socket of any suitable form may be inserted from the rear into the projecting portion, with the screw shell in register with the lamp opening in said portion.

The invention further contemplates the provision of simple means whereby the lamp socket, after being inserted in the shell, may be locked in lamp receiving position. The preferred embodiment of this means consists of a clamp fastened to the shell and adapted to engage a portion of the insulating body of the lamp socket for holding it in fixed position. When the fixture is provided with a convenience outlet, the means for fastening the fixed contacts of said outlet is utilized for fastening the clamp.

The particular ornamental design of the fixture disclosed herein is described and claimed in

a separate application for design Letters Patent, filed by me in the United States Patent Office, September 19, 1935, Serial No. 58,618. This application is restricted to the mechanical construction of the fixture described hereinafter.

In the drawings is shown, for the purpose of illustrating the invention, a fixture adapted for use as a wall bracket, in which Figure 1 is a front elevation of the fixture;

Fig. 2 is a central vertical sectional view of the same on line 2—2 in Fig. 1, looking from right to left;

Fig. 3 is a transverse sectional view of the same on line 3—3 in Fig. 1, looking downwardly;

Fig. 4 is a rear view of the fixture;

Fig. 5 is a rear view of the bottom portion of the fixture, with the insulating plate which holds the convenience outlet contacts in place removed, this view showing one contact in place and the other removed to show the contact recess;

Fig. 6 is a vertical sectional view on line 6—6 in Fig. 5, showing a convenience outlet contact and slot for receiving the blade of a plug;

Fig. 7 is a similar view on line 7—7 in Fig. 5;

Fig. 8 is a side elevation of a convenience outlet contact with lead wire attached.

Referring to the drawings, there is shown an electric light fixture made in accordance with my invention and adapted for use as a wall bracket which comprises a hollow shell of insulating material, a lamp socket mounted therein with clamping means for locking the socket in fixed position.

The shell may be of any suitable form, but, as shown, comprises a base portion 10 for engaging a wall or other supporting surface, and a projecting portion 11 for housing the electric lamp socket, which portion is provided with an opening 12 for the insertion of an electric lamp in the socket. The shell is open in its rear face and the base has a flanged edge 13 which forms a chamber 14 thereunder opening into the chamber 15 in the projecting portion 11. In external configuration, the base is in the form of a shield with the projecting portion 11 positioned in its lower part.

Within the chamber 15 is mounted an electric lamp socket comprising an upper block 16 and a lower block 17 of insulating material fastened together in spaced relation, a switch 18 mounted between the blocks and a lamp receiving screw shell 19 fastened to the top face of the upper block 16. The lower block 17 is preferably of heavier construction and of greater horizontal

dimensions than the upper block 16 for the purpose of imparting stability to the socket (Fig. 2).

The chamber 15 is preferably formed with parallel side walls 20 and 21 joined together at their front ends by a wall 22, which is semi-circular in horizontal section (Fig. 3), and the floor 23 of the chamber is parallel with the ceiling 24 thereof (Fig. 2). This form of construction of the chamber 15 permits the lamp socket to be inserted into the projecting portion sidewise and the dimensions are such that the lower insulating block 17 fits snugly within the chamber. Preferably, when the lamp socket is in position in the chamber, the top end of the screw shell 19 projects partially through the circular opening 12 in the top face of the projecting portion 11. This necessitates tilting the socket slightly when inserting it into the projecting portion, but the projection of the top end of the shell into the opening tends further to stabilize the lamp socket and to prevent lateral movement thereof.

Although the socket may include any suitable switch mechanism, it is shown as provided with a switch of the construction disclosed in United States Letters Patent No. 1,700,791, issued to Morey & Brogden on November 7, 1911, and adapted to be operated by a pull chain 26 which runs laterally from the switch down through an opening 28 in the lower block 17 and out through an opening 30 in the portion 11 (Figs. 2 and 3). The opening 28 is in the extended portion of the lower block, some distance inwardly from the switch, so that the force exerted by the chain on the switch when it is pulled is in a horizontal direction which insures perfect operation of the switch at all times.

For fastening the lamp socket in fixed position within the shell, any suitable clamping means may be provided and one form of such means is shown comprising an L-shaped clamp 32, having one end engaging a shoulder 34 formed in the lower block 17 of the socket and its other end fastened to the shell. Preferably, the latter end of the clamp is tapped with a threaded hole 45 and is inserted in a square recess 36 formed in the floor 23 and is fastened therein by a screw 38 mounted in a bore 40 in the shell. The axis of the threaded hole is inclined downwardly in relation to the long arm of the clamp so that when the screw 38 is tightened, the short arm is fulcrumed on the top edge of the rear wall of the recess to cause the long arm to exert a downward pressure on the shoulder 34.

The fixture may be provided with a convenience outlet and one such is shown in the drawings as arranged in the bottom end of the shell, and, for this purpose, that end of the shell is provided with a solid portion 42 which is recessed to afford a pair of parallel jack blade slots 44 and for holding a pair of contacts 46. In vertical section, the portion 42 is approximately triangular, having a transverse vertical face 48, a top face which is a continuation of the floor 23, and an oblique outer face 49 out of which the slots 44 open and which is flat for plug engagement. In the vertical face 48 is formed a transverse recess 50 which is triangular in vertical section (Fig. 7), one of the walls of the recess being horizontal and the other, oblique. The two jack blade slots 44 are parallel with the oblique wall of the recess 50 and open out through it into said recess (Fig. 6) the full height of said wall, thereby dividing the oblique wall into three sections (Fig. 5).

Above the recess 50 and on the outer side of each slot 44 is another recess 52 which opens

into the slot and also out through the floor 23 (Figs. 5, 7 and 3). Each of the contacts 46 comprises a base (designated as 46) and a blade portion 54 which is turned at right angles to the base and then in a reverse direction (Fig. 5 8). Each of said contacts is arranged with its base in a recess 52 and its blade portion in the adjacent slot 44 (Fig. 5) and to the base is attached by solder 55 a lead wire 56. To hold the base against upward movement, a V-shaped countersink 58 is formed in the outer wall of the recess 52 into which the end of the base projects. For holding the contacts in position in the slots, a cover 60 of stiff fibre board or other material, is mounted in the recess 50 with its bottom edge in the angle formed by the meeting of the two walls of the recess, and when it is fastened at its top edge to the shell by the screw 38, the bottom edge is locked. It will be observed that the screw 38 thereby performs two functions, namely, fastening the clamp 32 in addition to the cover.

The assembling of the fixture is a very simple matter. The lamp socket is inserted sidewise in the shell, the pull chain being dropped through the opening 30, and is slightly tilted to enter the end of the screw shell into the lamp opening 12, after which it is pushed against the curved end of the projecting portion. The clamp is then placed in position with one end in the floor recess and the other end engaging the shoulder in the socket block. The contacts are next inserted in place, the cover 60 adjusted and the screw 38 inserted in the bore 40 and screwed into the clamp, thereby causing the free end of the clamp 35 to bear down on the shoulder to lock the socket in place. The tightening of the screw fastens the cover 60 to hold the contacts securely in operative position.

In use, the fixture is fastened to an outlet box 40 set in the wall or other supporting surface, with its flange 13 in engagement with the said surface, and for this purpose it is provided with a circular opening 64 for receiving a headed bolt (not shown) for fastening the fixture to the cross bar of the outlet box. The lamp socket and the convenience outlet are connected to circuit carrying wires in the usual well-known manner.

After the fixture has been placed in position, an electric lamp 65 of any suitable form may be 50 threaded into the screw shell of the socket. Since the socket fits within the projecting portion of the fixture with its screw shell portion projecting into the lamp opening, the clamping means serves to lock the socket in fixed position so that the strains imposed by screwing a lamp into or out of the socket produce no movement thereof.

It will be observed that my invention provides a fixture of extremely simple construction, which is easily assembled and which requires but one 60 fastening means, even when a convenience outlet is included therein.

Another advantage of my invention is that the shell carrying the operative parts is so formed that when made of porcelain, it may be molded 65 out of a semi-dry mixture by the use of dies, so that I avoid the long delays and the expense of numerous molds involved in the method of casting the shells from a wet mixture.

Although I have shown in the present embodiment of the invention, a fixture including a lamp socket of particular form, it is not to be restricted to that form, since any form of socket may be used by slight modifications in the dimensions of the socket chamber in the fixture.

It is further to be understood that my invention is not to be limited to the precise form herein shown and described, since it may be embodied in various other forms of construction within the scope of the following claims.

What I claim is:

1. A device of the character described comprising a hollow shell of insulating material having a base portion adapted to engage a wall or other supporting surface and a lamp socket holding portion provided with a lateral opening, said shell having a small interior recess and a bore entering said recess from the inner face of said shell, a lamp socket, including an insulating body, switch and lamp receiving screw shell, fitted sidewise in and seated on the floor of said portion with its screw shell in register with said opening, said insulating body being provided with a shoulder, a clamp having one end seated in said interior recess and its other end engaging said shoulder on said insulating body and a screw mounted in said bore and threaded through the seated end of said clamp in said recess for holding said lamp socket in fixed position in said shell.

2. In a device of the character described, the combination of a hollow shell of insulating material comprising a base portion having an interior angular recess and a projecting socket holding portion provided with an opening, a lamp socket mounted in said projecting portion in register with said opening, a clamp having one end engaging said lamp socket, a convenience outlet formed in said base portion and comprising a pair of contact chambers opening out said angular recess in said base, a pair of parallel jack blade slots opening out said shell from said chambers, a pair of contacts loosely mounted in said chambers, each of said contacts being provided with a blade portion positioned in the slot communicating with said chamber, an insulating cover in said angular recess for closing said contact chambers and for holding said contacts therein, the lower edge of said cover projecting into the angular portion of said recess and a screw mounted in said base for fastening said cover thereto and for fastening said clamp to lock said socket against movement.

3. In a device of the character described, the combination of a hollow shell of insulating material comprising a base portion having an interior angular recess and a projecting socket holding portion provided with an opening and with a floor recess, a lamp socket mounted in said projecting portion in register with said opening, a right-angled clamp having one end engaging said lamp socket and its other end seated in said floor recess, a convenience outlet formed in said base portion and comprising a pair of contact chambers opening into said angular recess in said base, a pair of parallel jack blade slots opening out said shell from said chambers, a pair of contacts loosely mounted in said chambers, each of said contacts being provided with a blade portion positioned in the slot communicating with said chamber, an insulating cover mounted in said angular recess for closing said contact chambers and for holding said contacts therein, the lower edge of said cover projecting into the angular portion of said base recess and a screw mounted in said base for fastening said cover thereto and for fastening said clamp, said screw having its end threaded through the seated end of said clamp obliquely to force the other

end of said clamp downwardly to lock said socket in fixed position.

4. A device of the character described comprising a hollow shell of insulating material having a projecting portion provided with an opening and a recess in its floor and having a thickened portion provided with an angular recess in its interior face, a lamp socket mounted in said projecting portion in register with said opening, a clamp having one end mounted in said recess and its other end engaging said lamp socket, a pair of contact chambers formed in said thickened portion of said shell and opening out said angular recess, a pair of parallel jack blade slots opening outwardly from said contact chambers, a pair of contacts mounted loosely in said chambers, each of said contacts being provided with a blade portion positioned in the slot communicating with said chamber, an insulating cover mounted in said angular recess for closing said contact chambers and for holding said contacts therein, and a screw for fastening said cover to said thickened portion of said shell with its lower edge locked in said angular recess, the inner end of said screw being threaded through that arm of the clamp within said floor recess for fastening said clamp in operative position to lock said socket against movement.

5. A device of the character described comprising a hollow shell of insulating material having a projecting portion provided with an opening and a recess in its floor and having a thickened portion, a lamp socket mounted in said projecting portion in register with said opening, a clamp having one end mounted in said recess and its other end engaging said lamp socket, a pair of contact chambers formed in said thickened portion of said shell, a pair of parallel jack blade slots opening outwardly from said contact chambers, a pair of contacts mounted in said chambers, each of said contacts being provided with a blade portion positioned in the slot communicating with said chamber, a cover mounted on the interior face of said thickened portion for closing said contact chambers and for holding said contacts therein, and a screw for fastening said cover to said thickened portion of said shell, the inner end of said screw being threaded through that arm of the clamp within said floor recess for fastening said clamp in operative position to lock said socket against movement.

6. A device of the character described comprising an insulating body having a hollow projecting portion provided with an opening, a lamp socket, including a lamp receiving screw shell, fitted and seated in said projecting portion with said screw shell in register with said opening for receiving a lamp bulb inserted through said opening, a clamp having one end engaging said lamp socket, a pair of contact chambers formed in said insulating body and opening out the front face of said body through a pair of parallel jack-blade slots, each of said chambers opening out on two sides on the inner face of said body for permitting the insertion and seating of a contact therein, a cover for holding said contacts in said chambers and means for fastening said cover to said insulating body, said means being adapted for fastening the other end of said clamp to said insulating body to hold said socket firmly seated in said projecting portion.

7. A device of the character described comprising an insulating body having a hollow portion with an opening therein, a lamp socket, including a receiving screw shell, fitted and seated in

said hollow portion with said screw shell in register with said opening for receiving a lamp bulb inserted through said opening, a clamp having an end engaging said lamp socket, a convenience plug contact positioned in a chamber formed in said insulating body, a cover for holding said contact in the chamber, and a single member engageable with the clamp and the cover for securing the same to the insulating body whereby the socket and plug contact are secured and held in position by said single member.

8. A device of the character described comprising an insulating body having a hollow portion with an opening and a recess therein, a lamp socket including a receiving screw shell, fitted and seated in said hollow portion with said screw shell in register with said opening for receiving a lamp bulb inserted through said opening, a clamp having an end engaging said lamp socket and an angular extension received in the recess of the insulating body, a convenience plug contact positioned in a chamber formed in said insulating body, a cover for holding said contact in the chamber, and means engageable with the angular

extension of the clamp for securing the clamp and cover to the insulating body to hold said socket and plug contact in position within the insulating body.

9. A device of the character described comprising an insulating body having a hollow portion with an opening and a recess therein, a lamp socket including a receiving screw shell, fitted and seated in said hollow portion with said screw shell in register with said opening for receiving a lamp bulb inserted through said opening, a clamp having an end engaging said lamp socket and an angular extension received in the recess of the insulating body, a convenience plug contact positioned in a chamber formed in said insulating body, a cover for holding said contact in the chamber, and means engageable with the angular extension of the clamp for securing the clamp and cover to the insulating body to hold said socket and plug contact in position within the insulating body, an edge of the recess forming a fulcrum for the clamp.

ARTHUR A. JOHNSON.
